US00D753144S

(12) **United States Design Patent**
Seo et al.

(10) **Patent No.:** **US D753,144 S**
(45) **Date of Patent:** **** Apr. 5, 2016**

(54) **DISPLAY SCREEN OR PORTION THEREOF
WITH ICON**

(71) Applicant: **Samsung Electronics Co., Ltd.,**
Suwon-si, Gyeonggi-do (KR)

(72) Inventors: **Jang-Won Seo**, Seoul (KR);
Yong-Hwan Kwon, Sungnam-Si (KR)

(73) Assignee: **SAMSUNG ELECTRONICS CO., LTD. (KR)**

(**) Term: **14 Years**

(21) Appl. No.: **29/489,338**

(22) Filed: **Apr. 29, 2014**

(30) **Foreign Application Priority Data**

Dec. 30, 2013 (KR) 30-2013-0066507
(51) **LOC (10) Cl.** **14-04**
(52) **U.S. Cl.**
USPC **D14/485**
(58) **Field of Classification Search**
USPC D14/485-488
CPC G06F 3/1251; G06F 17/14

(57) **CLAIM**

The ornamental design for a display screen or portion thereof with icon, as shown and described.

DESCRIPTION

FIG. 1 is a front view of a display screen or portion thereof with icon, showing our new design; and,

FIG. 2 is a front view thereof, as shown in a display screen environment.

The broken lines are for environmental purposes only and form no part of the claimed design. The dot-dash broken lines represent unclaimed boundary lines and form no part of the claimed design.

1 Claim, 2 Drawing Sheets
